UNITED STATES PATENT OFFICE.

GEORGE S. G. SPENCE, OF BOSTON, MASSACHUSETTS.

IMPROVEMENT IN APPARATUS FOR DISTILLING SEA-WATER.

Specification forming part of Letters Patent No. 29,015, dated July 3, 1860.

To all whom it may concern:

Be it known that I, G. S. G. SPENCE, of Boston, in the county of Suffolk and State of Massachusetts, have invented a new and Improved Construction of Apparatus for Obtaining Fresh Water from Sea-Water, and which is also capable of being applied to other similar purposes; and I hereby declare that the following is a full and exact description thereof, reference being had to the accompanying drawings and references, which make part of this specification.

The nature of the invention consists in the arrangement and combination of a boiler with a movable condensing apparatus and a funnel-receptacle within the chamber of the boiler for discharging the condensed distillate therefrom.

In the accompanying drawings and references, Figure 1 shows a vertical section of the boiler, condenser, and receptacle; Fig. 2, an elevation of the same apparatus with the stop-cock for discharging steam and air in the commencement of the process; Fig. 3, a siphon shown in section and of peculiar construction, to be filled by means of a blast of air through it.

Let A A represent the sides of the boiler; A', the bottom, which may be received into the usual opening in the top of a cooking-stove or range.

B is the funnel-receptacle, receiving the condensed vapor from the under side of the condenser and conducting it off by the discharge-pipe c.

C represents the condensing-surface of the condenser to be filled with cold water to line f, or even higher.

D is a stop-cock for the discharge of air and steam when the boiler is first put in operation, and may be afterward closed.

E is a depression or groove on the outside of the flange F F, designed to receive the ascending portion of pipe c, which, as herein shown, rises on the inside and discharges its contents at or near the middle of the height of the boiler, but might equally well be so arranged as to discharge at c', which would have the effect of keeping pipe and receptacle B clear throughout its length, and thus avoid the necessity of the depressed groove E. The condensing apparatus C F E, &c., is supplied

with suitable handles, b b, and projecting flange F F, which rests on the shoulder x x, and is made removable, as seen in the drawings. It is designed that the flange F F shall be parallel with and nearly in contact with the sides of the boiler, whether groove E be used or not. Receptacle B is made with a very short trumpet-mouth to receive the drip from the inverted cone C, and should be barely large enough to receive the drip of condensed liquid with certainty from the point of the inverted cone, and since the flange F F comes nearly into contact with the sides of the boiler the area of the funnel-mouth B need not be larger than that of a silver dollar, or thereabout. This proportion gives almost the entire surface of the condensing-bottom C to the direct action of the ascending currents of steam and produces greatly-increased rapidity of condensation.

In the arrangement of this apparatus it is desirable that it be made comparatively broad and low to obtain an increased condensing-surface, and to bring that surface as near as may be to the surface of the boiling liquid without coming so near as to receive the spray and rupture of the bubbles produced from boiling. When this apparatus is used for obtaining fresh water from sea-water, a principal use designed by this invention, this intervening space will be regulated by practice, and will be governed by the strength of the fire, the exposure of the boiler-bottom, &c. Strong fire and nearness to the fire would require a greater distance between the boiling-surface of the liquid and the bottom of the condensing-surface, while low fire would require a diminished space. These involve skill and not invention. It is also practicable to suspend a vessel under the condensing-apex in place of the funnel-receptacle above named. The width of the bottom of the boiler is also part of the consideration of the distance between the boiling and condensing surface. The amount of water condensed will also depend upon the amount of fire-surface exposed.

When the boiler is to be kept in constant action, as in the caboose of a ship at sea, the usual supply-pipes for cold water and for discharging the heated water from the condenser are used and need not be described here. For temporary purposes, however, a siphon, G, of

peculiar form, is used to discharge the hot water from the condenser. It consists of a small bent tube, *g i*, received and soldered into a larger tube, *h k*, as shown in Fig. 3, the mouth *k* being slightly trumpet form. This siphon is charged by dipping leg *g* into liquid *f* and blowing, with the lips applied at *k*, a short quick blast through the tube *h k*, when the water rises in leg *g* and continues to run off at *h* until the condenser is emptied.

Having now described my invention and

the mode of using the same, what I claim as new, and desire to secure by Letters Patent, is—

The arrangement of the receptacle *B*, in combination with the boiler *A* and condenser *C*, in the manner substantially as and for the purposes set forth.

GEO. S. G. SPENCE.
